HOT WATER DISPENSER

Charles C. Zahlman, Hackettstown, N.J., assignor to
A.E.I. Corporation, Bethlehem, Pa.

Filed Nov. 18, 1970, Ser. No. 26,054

Term of patent 14 years

Int. Cl. D15—08

U.S. Cl. D94—3

FIG. 1

FIG. 2

FIG. 3

FIG. 4

FIG. 5

FIG. 6

BY

FIG. 1 is a front elevational view of a hot water dispenser showing my new design;

FIG. 2 is a side elevational view;

FIG. 3 is a top plan view;

FIG. 4 is a rear elevational view;

FIG. 5 is a bottom view; and

FIG. 6 is a front elevation view with the front compartments swung outwardly.

I claim:

The ornamental design for a hot water dispenser, as shown.
